UNITED STATES PATENT OFFICE.

JEROME G. BOWER, OF CHICAGO, ILLINOIS, ASSIGNOR TO PRESSED STEEL CAR COMPANY, OF PITTSBURG, PENNSYLVANIA, A CORPORATION OF NEW JERSEY.

DOOR-OPERATING MECHANISM.

No. 904,875.

Specification of Letters Patent.

Patented Nov. 24, 1908.

Application filed March 10, 1908. Serial No. 420,149.

To all whom it may concern:

Be it known that I, JEROME G. BOWER, a citizen of the United States, and resident of Chicago, Cook county, Illinois, have invented 5 certain new and useful Improvements in Door-Operating Mechanism, of which the following is a full, clear, and accurate description, reference being had to the accompanying drawings, in which like reference characters refer to like parts, and in which:

Figure 1 is a sectional end elevation of a portion of a car end showing the subject of the invention, Fig. 2 is a side view of the same, Fig. 3 is a detail plan of the lever 15 socket, Fig. 4 is a detail sectional view on the line 4—4, Fig. 1, showing the stop for the operating pawl and, in dotted lines, the position to which the pawl is moved in reversing the same, and Fig. 5 is a detail section through the slotted casting showing the dog plate guide projection.

An object of the present invention is to provide an improved operating device for a rotatable shaft forming a part of the door 25 operating mechanism. In general terms such a device consists of a ratchet wheel keyed to the shaft and a bell crank carrying a pawl for driving said ratchet in either direction, said bell crank having formed 30 therein a suitable socket for an operating lever such as a crowbar, stake or other similar bar. In the mechanism there is also a dog for preventing backward movement on the ratchet during the door-closing operation 35 when the weight of the doors induces movement of the shaft and a safety cam located for preventing automatic displacement of said dog.

Another object of the present invention is 40 to provide improvements in the details of the construction of the aforesaid mechanism.

Although not shown in the drawings, it is to be understood that the shaft operated by the hereinbefore described device is connected 45 in any suitable manner with one or more car doors, such, for instance, as shown and described in patent granted to Lindstrom & Streib, No. 791,348, dated May 30th, 1905, and entitled "Car Door Mechanism", in 50 which a bodily movable rotatable shaft is employed for closing the doors and support-

ing the doors while in closed position. The shaft during the opening movement is moved from beneath the doors whereupon the latter are instantly forced open by their weight 55 and the weight of the lading thereon, the connection between the shaft and the doors quickly paying out and causing the shaft to rapidly rotate in the opening direction.

Referring now in detail to the drawings, 1 represents the end of the car to which is riveted 60 a casting 2, having a slot therein in which is located and adapted to travel a door-operating shaft 3, having connected thereto a two-way ratchet 4 and having 65 loosely mounted thereon a bell crank 5. Bell crank 5 carries on one arm a projecting lug or pivot 5^a on which is loosely mounted an offset pawl 6 held in place by a cotter pin 7 passing through a perforation in the lug or 70 pivot 5^a. Lug or pivot 5^a is provided with an inclined upper surface at 5^b.

5^c is a pawl safety stop projecting slightly over the lug or pivot 5^a and also formed integral with bell crank 5. 5^d is a socket 75 formed in the other arm of bell crank 5 of suitable size and shape to receive a crowbar, stake or other similar bar or handle. The socket 5^d tapers at its bottom and extends entirely through the arm so that the arm is 80 tubular or perforated.

8 is a dog pivotally mounted on a plate 9 and adapted to engage with the two-way ratchet 4. Plate 9 is carried by and adapted to travel with shaft 3, and 10 is a cam safety 85 latch engaging the dog 8 to prevent automatic displacement of dog 8, such as by jar-ring of the car in transit.

9^a is a stop or rest integral with plate 9 for supporting latch 10 in disengaged position.

9^b is a stop integral with plate 9 for preventing dog 8 from dropping below the horizontal when in disengaged position. Plate 9 is preferably formed of a casting and is 95 provided with an inwardly extending projection 9^c which travels in the slot in casting 2 and prevents plate 9 from dropping below horizontal position.

The advantages of the construction described are that any crowbar, stake or other bar lying about the railway yards, where the

doors are to be operated, may be inserted in the socket 5^a and the shaft thus operated without necessity of carrying a lever attached to or integral with the bell crank 5. 5 These have been found objectionable as in cases these levers have been known to become disengaged from their fastening means, whereupon they dropped down toward the tracks, catching the ties and doing considerable damage not only to the lever but to the roadbed. This is especially the case when one of these levers is formed of a metal bar, as is frequently the case.

A further advantage of the structure described is that the pawl carried by the bell crank 5, during a runaway movement of the shaft during the opening of the doors is prevented from flying up and over to its door-closing position, causing the lever to be jerked from the hands of the operator. This has been known to happen and the operator to be seriously injured. Such an automatic movement of the pawl at such a time would be caused by rebounding of the pawl from 25 the teeth of the ratchet. The inclined surface 5^b on lug 5^a allows tilting of the pawl, shown in Fig. 4, whereupon by reason of its offset the pawl may be turned beyond the stop 5^c and thus reversed.

30 Another advantage of the structure described is that the plate 9 is held against rotation about the shaft 3 by an inward projection 9^a in engagement with the slot, so that the dog 8 operates effectively against the teeth of the ratchet 4.

By mounting a bell crank on shaft 3 to drive same, a much greater range of positions of the operating handle in which the mechanism may be started with pawl held in 40 engagement by gravity, so that the operating handle may be conveniently operated from the ground or from the end sill without necessitating the holding of pawl 6 by hand in engagement at the start of the stroke. 45 This is because with a convenient position

of the operating handle at the start of any operative stroke the pawl arm of bell crank 5 occupies a position within a range of 90 degrees above the horizontal in which position the pawl 6 must hang to either one side or other of the vertical, except when the pawl arm is on the vertical, hence pawl 6 is held in contact by gravity. If during an operative stroke the pawl arm is moved beyond the range of 90 degrees above the horizontal, the pawl 6 is held in engagement by contact with the tooth on ratchet 4.

Having thus described my invention, the following is what I claim as new therein and 60 desire to secure by Letters Patent:-

1. In a door operating mechanism, a shaft, a bell crank having a lever socket formed therein loosely mounted on said shaft and

a connection between said bell crank and shaft for turning the latter.

2. In a door operating mechanism, a shaft and a cast metal lever having a tapered aperture extending through one arm at right-angle thereto, carried by said shaft for turning the same.

3. In a door operating mechanism, a shaft and a metal lever mounted on said shaft having a handle socket formed therein and a tapered aperture at the base of said socket.

4. In a door operating mechanism, a ratchet, a lever, a pawl carried by the lever for operating the ratchet and a stop formed on the lever integral therewith for preventing displacement of the pawl.

5. In a door operating mechanism, a two-way ratchet, a lever, a lug on the lever having an inclined face, a pawl carried by the lug and a pawl stop projecting over the lug.

6. In a door operating mechanism, a two-way ratchet, a lever, a lug on the lever having an inclined face, an offset pawl carried by the lug and a pawl stop projecting over the lug.

7. In a door operating mechanism, a shaft, a ratchet for driving said shaft, a lever having a handle socket formed in one arm and a pawl carried by the other arm of said lever for driving said ratchet.

8. In a door operating mechanism, a shaft, a ratchet for driving said shaft, a lever of cast metal having a cylindrical handle socket in one arm and tapered pawl lug or pivot on its other arm, and a pawl safety stop integral with and projecting therefrom above said lug or pivot in combination with the offset pawl carried by said lug or pivot.

9. In a door operating mechanism, a slotted plate, a shaft movable bodily through the slot in said plate, a ratchet carried by said shaft, a dog frame carried by said shaft projecting into the slot in said plate to prevent rotation about said shaft and a dog carried by said frame.

10. In a door operating mechanism, a slotted plate, a shaft movable bodily through the slot in said plate, a ratchet carried by said shaft, a dog frame carried by said shaft projecting into the slot in said plate to prevent rotation about said shaft and a dog and safety dog latch carried by said frame.

11. In a door operating mechanism, a slotted plate, a shaft movable bodily through the slot in said plate, a ratchet carried by said shaft, a dog frame carried by said shaft projecting into the slot in said plate to prevent rotation about said shaft and a dog and cam safety dog latch carried by said frame.

12. In a door operating mechanism, a slotted casting, a shaft movable bodily through the slot in said casting, a ratchet carried by said shaft, a cast metal plate carried by said

shaft and having an offset projecting into the slot in said casting, a dog carried by the plate and adapted to engage the ratchet, a cast metal lever having a handle socket formed in one arm carried by said shaft and a pawl carried by the other arm of said lever.

The foregoing specification signed at McKees Rocks, Allegheny county, Pennsylvania, this 4th day of March, 1908.
